UNITED STATES PATENT OFFICE.

EDWIN C. BRUEN, OF BROOKLYN, NEW YORK, ASSIGNOR OF ONE-FOURTH TO NORMAN W. HENLEY, OF NEW YORK, N. Y.

METHOD OF FORMING PLATE-HIGH LINOTYPE PRINTING-PLATES.

No. 872,794.

Specification of Letters Patent.

Patented Dec. 3, 1907.

Application filed April 26, 1907. Serial No. 370,365.

To all whom it may concern:

Be it known that I, EDWIN C. BRUEN, a citizen of the United States, and resident of Brooklyn, in the county of Kings and State of New York, have invented certain new and useful Improvements in Methods of Forming Plate-High Linotype Printing-Plates, of which the following is a specification.

My invention relates to a novel method of making printing plates from a plurality of "plate-high" linotype-bars whereby thin integral plates may be practically and economically produced, and my invention includes the product resulting from the practice of the said method.

My invention is practically designed to produce type-matter from a novel form of linotype. In the operation of "linotype machines" a series of matrices are employed, and these matrices representing type forming characters are automatically presented across the open front of a mold in order to produce the type characters in relief on the bar or linotype cast in the mold. The type-bars thus produced are familiarly known as "linotype slugs" and these are cast "type-high" which greatly increases the cost of production.

The main feature which characterizes my invention resides in making the type-bars or "slugs" "plate-high", that is to say of approximately the height of a stereotype plate, and then producing thin integral printing plates therefrom as the linotype "slugs" are delivered from the machine.

In the accompanying drawing illustrating my invention in the several figures of which like parts are designated by similar numerals of reference: Figure 1, is a top plan view in perspective of a plate composed of a series of type-bars or "slugs" and embodying my invention, and Fig. 2, is a broken away bottom plan view thereof. Fig. 3, is a fragmentary detail view of the binding and soldering means I prefer to employ to make the plates.

In the drawing 2, designates the type-bars or "slugs" of my invention. These type-bars or "slugs" 2, are to be cast, of very much less depth than the linotype-slugs commonly employed, for instance the latter being about $\frac{1}{8}$ of an inch in height while my type-bars or "slugs" 2 will be about $\frac{1}{2}$ of an inch, or substantially of the same height or

thickness as a stereotype plate. This constitutes an important advantage of my invention as will obviously appear from a commercial standpoint because of the initial saving of metal.

The type-bars or "slugs" 2 are preferably formed with beveled edges 3, and any number of these type-bars 2, may be united to each other to make a printing plate 4. I prefer to make the joint, or union of the type-bars or "slugs" in producing the plates by the following means, although I do not wish to be limited to this precise construction viz:—5 designates longitudinal grooves formed in the beveled edges of each bar 2, and 6 a wire composed of soldering material and adapted to engage the contiguous grooves 5 when the requisite number of bars 2, are aligned to form a plate 4. The wire solder 6, is first forced or pressed into the contiguous grooves 5, thus binding the bars 2, together before fusing and at this stage of the operation corrections can be made by substituting a correct bar 2, for an imperfect one whenever necessary. The wire 6, being composed of soft metal it can be easily removed from and inserted into the grooves 5. The facility with which corrections can be made is another important advantage of my invention which will be readily appreciated by those skilled in the art. The next step in making the plates 4, consists in melting the binding wire-solder 6, by the application of a heated iron, or in other suitable manner. This completes the operation of making a printing plate 4, "plate-high" and composed of a series of bars united together as described.

For general press work the plates 4, being provided with beveled edges 3, may be made up in the usual manner and patent blocks and any suitable chase may be employed.

What I claim as my invention and desire to secure by Letters Patent is:

1. The herein described method of forming a "plate-high" printing plate consisting in first casting a series of linotype-bars "plate-high" then binding said type-bars together and then uniting the same by fusing, substantially as set forth.
2. The herein described method of forming a "plate-high" printing plate consisting in first casting a series of linotype-bars

"plate-high" then binding said type-bars together, and then fusing the binding agent to unite said bars, substantially as described.

3. The herein described method of forming a "plate-high" printing plate consisting in first casting a plurality of linotype-bars "plate-high" then binding said bars together as the latter are delivered from the machine and assembled, and then fusing the binding 10 agent to unite said bars, substantially as set forth.

4. The herein described method of forming a "plate-high" printing plate consisting in first casting a plurality of linotype-bars 15 "plate-high" with beveled edges having a semi-circular groove therein, then inserting a fusible soldering wire in said groove to

bind the bars together and then fusing said wire to unite said bars, substantially as set forth.

20

5. A "plate-high" printing plate consisting of "plate-high" linotype bars provided with beveled edges having a semi-circular groove therein and a binding and soldering wire fused in said groove substantially as 25 described.

Signed at New York city in the county of New York and State of New York this 15th day of March A. D. 1906.

EDWIN C. BRUEN.
